FLUID FUEL BURNER

Henry F. Morrell, Denver, Colo.

Application October 1, 1943, Serial No. 504,647

5 Claims. (Cl. 158—74)

This invention relates to improvements in fluid fuel burners.

The use of oil and gas for fuel in connection with power and heating plants is quite common and in order to use such fuel to the best advantage, it must be mixed with the proper amount of air so as to obtain complete combustion and where liquid fuel is employed, means must also be provided to properly atomize it so as to reduce it to the consistency of a fine mist that will be completely oxidized during the burning operation.

It is the object of this invention to produce a burner of a simple and substantial construction that shall be so designed that it will permit adjustments to be made for the purpose of effecting an atomization and a supply of air for combustion so proportioned to the fuel that practically all of its thermal units will be converted into heat.

Another object of this invention is to produce a fuel burner of the type mentioned which shall have means for discharging the fuel in a hollow stream and providing air for combustion both on the outside and on the inside of such stream.

Another object of this invention is to produce a fluid fuel burner that can be used with oil or with gas as fuel.

A further object of this invention is to produce a burner that shall be provided with an inspirator body of a Venturi shape in which a fuel mixing and atomizing device is axially positioned and in which streams of air or steam are admitted through helically arranged openings positioned adjacent the inner surface of the wall whereby an inspirator action is obtained that causes a hollow stream of air to flow helically through the inspirator body and in which the fuel is arranged to be discharged in a helical stream adjacent the center and which, in addition, is provided with means for supplying a stream of air to the center of the hollow fuel stream so as to permit complete combustion of the fuel at the center of the stream.

Another object of this invention is to produce a burner of such construction that the amount of fuel can be adjusted independently of the quantity of steam employed for atomizing the fuel and in which the amount of atomizing fluid and fuel can be simultaneously adjusted in a predetermined proportion.

A further object of the invention is to produce a burner of such construction that it can be readily cleaned by means of steam under pressure and which can therefore be kept free from

accumulations of soot and other objectionable deposits.

The above and any other objects that may become apparent as this description proceeds are attained by means of a construction and an arrangement of parts that will now be described in detail and for this purpose reference will be had to the accompanying drawings in which the invention has been illustrated in its preferred embodiment, and in which:

Figure 1 is a longitudinal diametrical section taken on plane 1—1, Figure 3;

Figure 2 is an enlargement of a fragmentary portion of the burner shown in Figure 1;

Figure 3 is an end elevation looking upwardly in Figure 1;

Figure 4 is a section taken on line 4—4, Figure 5; and

Figure 5 is a section taken on line 5—5, Figure 1.

In the drawings reference numeral 10 designates an inspirator body which is roughly of Venturi shape. The end which has been designated by reference numeral 11 is of a larger diameter than the central portion which has been designated by numeral 12 and the inner end 13 is outwardly flaring. In the embodiment shown, that part designated by reference numeral 13 is threadedly or otherwise connected to the other part of the burner at the point indicated by reference numeral 14. Extending outwardly at the joint 14, is a flange 15 whose inner surface is finished and which is provided with a plurality of openings 16 for the reception of bolts by means

35 of which the burner is secured in place on a boiler or other heating apparatus. An annular chamber or manifold 17 is provided adjacent the narrowest portion of the inspirator body and the front wall is exposed in the manner shown in Figure 1 so as to provide an annular surface which is provided with a plurality of helically inclined perforations 18. In the embodiment illustrated, perforations 18 are inclined so as to produce a spirally directed circular blast of steam

45 rotating in a clockwise direction when viewed as in Figure 4. The outwardly flaring outer end of the inspirator body is provided with a machined surface 19 to which the burner base 20 is secured by means of tubular bolts 21 and 22. The surface 19 is machined so that it forms a portion of a frusto-conical surface whose axis coincides with the axis of the inspirator body. This is effected by first machining the surface 15 and securing the inspirator body to a face plate with the machined surface against the same. The

base 20 has a central opening 23 that has sections of different diameters and which is so positioned that it is in axial alignment with the inspirator body. A steam tube 24 is secured in the inner end of opening 23 and the wall of the latter is provided with an inwardly extending flange 25 that serves as an abutment for packing material positioned between this abutment and the movable ring 26. A removable abutment 27 is positioned in the enlarged section 28 of the burner base and serves as the inner abutment for packing material held in place by means of the packing ring 29. An atomizer control body 30 is positioned in the enlarged part of the enlarged section 28 of the opening 23 and is held against rotation by means of a screw 31 in the manner shown in Figure 5. The outer end of the control body 30 is threaded and cooperatively connected therewith is a cylindrical nut 32. This nut is provided at its inner end with a flange 33 and is secured to the burner base by means of a ring 34 that is held in place by means of screws 35. A handle 36 has a portion that surrounds the nut 32 and is held against rotation thereon by means of a key 37. The ring 34 is graduated into equal spaces by means of marks 38 over which the pointer 39 moves. The atomizer control body has an axial opening which is provided with a threaded section 40 and an enlarged section 41 with the inner surface of which a packing nut 42 is threadedly connected. A fuel feed control tube 43 extends through the atomizer control body and is threadedly connected therewith so that whenever the tube is rotated relative to the body, it will also move axially with respect thereto. The outer end of the tube 43 may be noncircular, for example, square; or it may be provided with a key slot like that designated by reference numeral 44. A control knob 45 surrounds the outer end of the tube 43 and is nonrotatably connected therewith. The nut 32 has an enlarged section at its outer end against the inner shoulder of which a washer 46 is positioned. A spring 47 is positioned in a groove in the wall of the enlarged portion and serves to hold the washer 46 from longitudinal movement. Bolts 48 pass through the knob 45 and through the washer 46 and their heads are spaced from the washer by means of springs 49. That portion of the handle 36 that surrounds the nut 32 is provided with a depression having a frusto-conical surface 50 that cooperates with the frusto-conical surface 51 on the feed control knob 45. The action of the springs 49 serves to urge the two frusto-conical surfaces towards each other, producing a friction clutch whose function will be hereinafter described. By pulling the knob 45 outwardly so as to release the friction between it and the handle 36, tube 43 may be rotated independently of the nut 32 but when the knob 45 is acted on by the springs 49, it will rotate in unison with the handle 36, thereby producing a simultaneous adjustment for a purpose that will hereinafter more fully appear.

A fuel atomizing tube 52 has its outer end secured in an enlargement of the axial opening in the atomizer control body 30. Openings 53 communicate the interior of tube 52 with the space surrounding the same, which, in turn, is in communication with the fuel inlet passage 54.

Referring now more particularly to Figure 2, it will be observed that the steam tube 24 is provided on its inner surface, adjacent its outer end, with an inwardly tapering frusto-conical surface 55 that connects the larger portion of its inner

surface with the smaller diameter section 56. The latter section is provided with a groove 57 to which reference will hereinafter be made. The fuel atomizing tube 52 is provided adjacent its inner end with a frusto-conical surface 58 that overlaps the frusto-conical surface 55 and which connects the larger diameter section with the smaller diameter section which has been designated by reference numeral 59. The latter terminates in an outwardly extending flange 60 of substantially the same diameter as the section 56 of the steam tube 24. That part of the fuel atomizer tube 52 that has been designated by reference numeral 59 is provided with a plurality of helically arranged and inwardly ranging openings 61 through which steam for atomizing the fuel will pass in the manner indicated by the arrows 62. Due to the helical arrangement of these openings, the steam for atomizing will issue in a helical rotating stream that serves to break up the particles of oil or liquid fuel and produce a fine atomization thereof. The inner surface of the atomizing tube 52 is provided with a forwardly tapering frusto-conical surface 63 and the fuel feed control tube 43 is provided near its inner end with a frusto-conical surface 64 that overlaps and cooperates with surface 63 to control the amount of fuel that is discharged. Tube 43, in addition to serving as a valve stem, also serves to introduce air to the center of the fuel stream whereby oxygen for fuel combustion is delivered to the interior of the flame in such a way as to assure a complete combustion.

Referring now to Figure 1, it will be observed that whenever nut 32 is rotated, it will move the atomizer control body longitudinally and therefore it will produce a relative movement of the steam tube 24 and the fuel atomizer tube 52, thereby changing the distance between the frusto-conical surfaces 55 and 58 whereby the amount of steam that can enter and pass through the openings 61 is adjusted. If nut 32 is rotated without at the same time rotating the knob 45 and the tube 43, the fuel feed adjustment will not be altered. But since the handle 36 is frictionally interconnected with the knob 45 so as to produce simultaneous rotation, it follows that whenever handle 36 is rotated, it not only changes the amount of steam admitted, but it also effects a simultaneous and proportionate adjustment of the fuel supply. This feature of the burner is of great importance for the reason that after the fuel and the atomizing steam has been once properly adjusted this adjustment will be altered whenever adjustments are made for a greater or lesser amount of heat.

To effect the initial adjustment, the operator grasps knob 45 and exerts a sufficient pull thereon to compress the springs 49 sufficiently to break the frictional interconnection between the knob and the handle 36, whereupon tube 43 can be adjusted relative to tube 52 and in the same manner it is possible to adjust the tube 52 with respect to both tubes 24 and 43, if this should become desirable.

Attention has been directed to the fuel passage 54 that has been provided in the burner base 20 and in addition to this, a steam passage 65 is provided which is in direct communication with the space between the steam tube 24 and the fuel atomizer tube 52. A fitting 66, which has been shown as a combination of a T and an L, has the opening 67 connected with a source of steam or of gas and this opening is also in communication with the opening 68 which leads

to the manifold 17. A valve 69 controls the flow of steam to the manifold. This valve is provided with a pointer 70 that moves over a graduated disk 71 and which indicates the amount the valve is open. The graduations 72 may be numbered and the graduations 38 on disk 34 may also be numbered and it is therefore possible to repeat any adjustment that has once been made. The adjustments for different installations are different and after they have once been determined, a record is made of the positions of the parts so that if this adjustment is disturbed, it may be re-established whenever desired. Although it has not been shown on the drawings, it is sometimes desirable to have the knob 45 provided with a pointer or with a mark and have the surrounding surface of the handle 36 provided with graduations whereby a record may be made of the relative positions of these two parts when the desired adjustments have been effected. Valve 69 is provided with a handle 69a for operating it. The members designated by reference numerals 21 and 22 are hollow bolts and the portions 21a and 22a that are in engagement with the base 20 are threadedly connected therewith and the outer portions are also threaded so as to cooperate with the nuts 21b and 22b, respectively. The tubular bolt 22 is connected with a source of oil or of gas which constitute the fluid fuel employed. Attention is now directed to the passage 73 that connects the steam passage 65 with the fuel passage 54. Passage 73 can be closed or opened by means of a valve whose stem has been designated by reference numeral 74. This valve stem is provided with a hand wheel 75 and with a stuffing box 76. When the valve is in open position, steam can pass through the passage 73 and into the space between tubes 52 and 43 and by this means any accumulation of soot at the burner tip can be quickly and completely removed by the use of the high pressure steam blast. When the tube 52 is withdrawn to the position shown in Figure 2, the flange 60 will be positioned in the groove 57 and the steam will then have a passage independent of the openings 61. When the parts are in the position shown in Figure 2, and the valve 74 in open position, the burner can be thoroughly cleaned and relieved of any accumulations of soot that would otherwise interfere with its operation.

Attention, in particular, is directed to the construction whereby the fuel is surrounded by an envelope of air circles in a helical direction produced by the inspirator action of the steam emerging through the openings 18 and to the construction whereby air for combustion is supplied to the center of the fuel stream so as to assure a complete combustion.

Attention is also directed to the adjustment by means of which the fuel and the steam for atomizing can be independently adjusted and after such adjustments have been effected, can be simultaneously adjusted in a predetermined proportion through the interaction of the rotating nut 32 and the knob 45. The construction by means of which the burner can be quickly cleaned by the action of the steam is also believed to be of great importance as this simple method of cleaning assures that the burner will be kept clean at all times.

When the burner is started after having been closed down over night, the oil will be rather stiff and therefore unsuited for use until heated. This is true in cool weather more particularly than in warm weather. When the oil is con-

gealed, gas is employed for producing sufficient heat to generate steam and heat the oil to a flowable condition. Before steam is generated, a gas under pressure is admitted into the passage 67 and takes the place of the steam for the purpose of producing a flow of air and for atomizing the fuel. However, when gas is used as fuel, there is no great need of atomizing as the fuel is already in a gaseous state.

The burner assembly comprising tubes 24, 43 and 52 is quite long and this gives the liquid fuel time to become highly heated so that when it is discharged at the inner end, it vaporizes very quickly.

Having described the invention what is claimed as new is:

1. A liquid fuel burner having three concentric tubes spaced to form two concentric annular passages, the outer tube being stationary, the passage between the innermost tube and the intermediate tube being in communication with a supply of liquid fuel, the space between the outermost and the intermediate tubes being in communication with a source of steam under pressure, the innermost tube being open for the free passage of air, valve means controlling the escape of fuel and of steam from the annular passages comprising, means for preventing the intermediate tube from rotating relative to the stationary outer tube while permitting relative longitudinal movement, means for moving the inner tube longitudinally relative to the intermediate tube, to control the fuel feed, means for simultaneously moving the inner and intermediate tubes as a unit, longitudinally relative to the outer tube, to control the flow of steam, and means for interconnecting the two moving means to effect a simultaneous adjustment of the fuel and steam feed controls.

2. A liquid fuel burner comprising, an elongated hollow inspirator body, a steam tube positioned centrally of the body, said tube being in communication with a source of steam under pressure, a fuel atomizing tube, said last mentioned tube being in communication with a fuel supply positioned in the steam tube, the inner surface of the steam tube and the outer surface of the fuel atomizing tubes having outwardly tapering frusto-conical surfaces in over-lapping opposed relation, means for moving the two tubes relative to each other to vary the cross sectional area of the annular passage between the two frusto-conical surfaces to regulate the amount of steam that can pass, a fuel feed control tube positioned within the fuel atomizing tube, the inner surface of the last mentioned tube and the outer surface of the fuel feed control tube having overlapping opposed frusto-conical surfaces forming an annular fuel control passage, means for moving the fuel feed control tube relative to the fuel atomizing tube, to vary the area of the fuel passage while the last mentioned tube remains stationary relative to the steam tube, means for moving the fuel atomizing tube relative to the steam tube while maintaining a fixed relation between the fuel atomizing tube and the fuel feed control tube, and means comprising a releasable clutch for interconnecting the two moving means to effect a simultaneous movement between the steam tube and the atomizing tube and the fuel feed control tube and the atomizing tube.

3. A liquid fuel burner comprising a tubular inspirator body, a burner base having an opening extending therethrough and a fuel and a

steam passage in communication with the opening, a steam tube having one end positioned in the opening in the base, an atomizer control body positioned in the other end of the opening and mounted for longitudinal movement therein, means for holding the control body from rotating relative to the base, said control body having a threaded axial opening, the outer surface having a threaded section, a fuel feed control tube extending through the opening in the control body and threadedly connected therewith, a fuel atomizing tube positioned in the space between the first mentioned tubes with one end secured to the control body, a nut rotatably connected with the base and threadedly connected with the control body for moving the latter longitudinally in the base when the nut is rotated, means for rotating the fuel feed control tube relative to the control body to effect an axial adjustment thereof relative to the fuel atomizing tube, and means comprising a clutch mechanism for simultaneously rotating the nut and the fuel feed control tube to effect a predetermined proportional adjustment between the fuel atomizing tube and the steam tube and between the fuel feed control tube and the fuel atomizing tube, the space between the fuel feed control tube and the fuel atomizing tube being in communication with the fuel passage and the space between the steam tube and the fuel atomizing tube being in communication with a steam supply.

4. A liquid fuel burner comprising, an inspirator body of elongated tubular form, a burner base secured to the inner surface near one end of the body, the base having an opening in axial alignment with the body, a steam tube having one end secured in the opening, the inner surface of the steam tube having a forwardly tapering rearwardly facing frusto-conical surface, an atomizer control body provided with an axial opening therethrough, positioned in the opening in the base for longitudinal movement therein, means for holding the control body from rotating, means for moving the control body axially comprising a nut rotatably connected with the base and threadedly connected with the control body, the latter having a threaded central opening, a fuel feed control tube extending through the opening and threadedly connected therewith, means for rotating the last mentioned tube, a fuel atomizing tube positioned in the annular space between the steam tube and the fuel feed control tube, the outer end of said atomizing tube being positioned in the inner end of the opening in the atomizer control body, the inner end of said atomizing tube terminating within the steam

tube and provided on its outer surface with a forwardly tapering frusto-conical surface overlapping and facing the frusto-conical surface on the inside of the steam tube, the inner surface of the fuel atomizing tube having an inwardly tapering frusto-conical surface, the inner end of the fuel feed control tube having an inwardly tapering frusto-conical surface facing the frusto-conical inner surface on the fuel atomizing tube, means for moving the fuel feed control tube relative to the fuel atomizing tube, means for moving the last mentioned tube relative to the steam tube, means for simultaneously adjusting the fuel atomizing tube relative to the steam tube and the fuel control tube relative to the fuel atomizing tube, the space between the fuel feed control tube and the fuel atomizing tube being connected with a liquid fuel supply and the space between the fuel atomizing tube and the steam tube being connected with a source of steam under pressure, and means for producing an inward flow of air through the inspirator body.

5. A burner for use with liquid fuel comprising, a tubular inspirator body, a burner base positioned in and secured to the inspirator body near its outer end, the base having an axial opening and separate steam and fuel passages in communication therewith, a steam tube secured in the inner end of the axial opening, the inner end of the tube having a portion of decreased diameter, an atomizer control body positioned in the opening in the base, said body having an axial opening which is threaded, a fuel atomizing tube secured in the inner end of the opening in the base in concentric relation therewith, a fuel feed tube passing through the opening in the base and threadedly connected therewith, means for resisting forces tending to rotate the control body relative to the base, means comprising a nut rotatably connected with the base and threadedly connected with the atomizer control body for moving the latter axially in the opening in the base, means for rotating the fuel feed tube to move it longitudinally relative to the control body and the fuel atomizing tube, the two last mentioned means being independently movable, and means comprising a friction clutch device for effecting a simultaneous operation of the two adjusting devices, whereby the fuel feed control tube will be moved relative to the fuel atomizing tube and the latter moved relative to the steam tube thereby effecting a simultaneous adjustment of the quantity of fuel and steam supplied, in a predetermined ratio.

HENRY F. MORRELL.
